ATTORNEY

UNITED STATES PATENT OFFICE.

THOMAS WIGHT, OF KANSAS CITY, MISSOURI.

COPING SEAL.

Application filed January 26, 1927. Serial No. 163,659.

My invention relates to coping on fire walls and more particularly to coping seals designed to seal and guard the joints of a coping course to prevent intrusion of moisture.

In present practice the top course of a firewall comprises usually a course of stone or tile often ornamental in design, the joints of which are cemented and therefore require some protection from weather so that moisture may not disintegrate the mortar or percolate interiorly of the fire wall. Many expedients have been restored to in order to provide a sealing means for this situation. Sometimes the blocks for coping are provided with integral joint shields, each block having an extended and projected lip under which the plane edge of an adjacent block is laid, the lip constituting a guard to protect the mortared jointure. This is an expensive process since waste is involved in providing the projection lip which must be raised above the plane of the coping as well as laterally extended, and hazard is involved of breaking the lip and so rendering useless the particular coping block. Another expedient is the provision of a metal cover for the entire coping laid on top of the coping blocks and of course, preferably not visible from the street or other position except on a level with or higher than the fire wall.

The desirability of providing an effective means of sealing the joints between coping blocks extends to the situation of a lintel or window sill stone or of a similar decorative course provided for buildings having brick outer walls and even for buildings constructed of concrete and for which coping courses are provided that have no structural necessity to call them forth.

I purpose to provide a means of sealing the joints between coping blocks in a course laid on a wall, which will avoid the disadvantages of the expedients referred to including the disadvantage of unsightliness of a continuous metal cover for a coping course and hazard of rust stains running down from the metal over the face of the wall, and that will provide an additional decorative element rather than a handicap to the appearance of a structure.

I provide in accomplishing this purpose a metal strip having depending, longitudinally bent-in portions and designed to be laid transversely of the coping wall, the edges of the strip resting on adjacent ends of coping

blocks and a strip secured to the coping by bolts projected through the strip and engaged with the adjacent under edges of the coping block or in the mortar.

My device will be more particularly described with references to the drawings in which:

Fig. 1 is a perspective view of a section of fire wall having coping equipped with my device.

Fig. 2 is a perspective view of the strip element of my device.

Fig. 3 is a perspective view from beneath my device showing the longitudinal flanges that guard the joints from the moisture.

Fig. 4 is a cross section on the line 4—4, Fig. 1, through a connecting bolt, showing adjacent coping blocks equipped with my device.

Fig. 5 is a cross section similar to Fig. 4, but remote from the connecting bolts.

Referring in detail to the drawings:

1 designates a fire wall, 2 coping blocks arranged in a finishing course thereon, 3 the mortar joints between the blocks 2, and 4 my device comprising a metal strip 5 covering the horizontal exposure of the joint and having apertures 6 for receiving bolts 7 projected through the joints 3 and wherewith the strip is secured in engagement with the blocks to protect the joint.

A bolt 7 is assumed to be erected adjacent a laid block, the bolt head 8 set in the mortar spread on the top of the fire wall 1, is flanges 90 projecting under the edge of a coping block, and a successive coping block laid to engage the flange also. The strips 5 may be installed as the work of laying the coping progresses, or any time after the wall is finished, since the protruding bolts, adequately anchored, are available for engagement with the strips and application of the nuts 9 whereby tight contact of the strips against the upper surface of the blocks is attained, for sealing the joints.

I provide a particularly novel structure for my strip to enhance the sealing effect and to produce a sealer having qualities of permanence, stability and efficiency. The sides 10 of the strip are downbent, preferably from longitudinal lines spaced from the median line to produce a ridge 11, and apertures 6 in said portion are provided with upstruck guards 12. The strip receives the bolts 6 by means of said apertures, the nuts 9 are applied to the bolts and threaded thereon, rest-

ing on the ridge 11, compression of the strip by the continued threading of the nuts forcing the aforesaid tight contact of the strip with the blocks, and tending to spread the strip laterally, a function that has peculiarly useful qualities because of features of structure now to be described.

The downbent sides 10 are folded inwardly and upwardly substantially adjacent the sides, forming portions which may be described as bearing arms and are designated 13. The edges are then downwardly bent to a position relatively at right angles with the said arms, and producing flanges 14. The construction is such that upon the downbending of the said flanges, the edges thereof project below the horizontal plane of the lines on which the sides are bent to produce the bearing arms 13. The result is that when the strip is positioned on adjacent blocks, the edges of the flanges rest on the surfaces of the blocks, and the exterior limits of the sides are spaced therefrom, as clearly disclosed in Fig. 4. The flanges therefore constitute a sealing factor of a strip in functioning position; and, as observable from the drawings the spacing of the bearing arms 13 is sufficient to admit a packing element 15 which will later be referred to and be more fully described.

The strips as shown in Fig. 1 installed on coping blocks having tapered surfaces 16 are bent at 17 to conform to such tapered surfaces. The ends 18 of the strips are bent over the edges of the blocks, providing protection for the joints at the outer edges of the blocks. I have illustrated a common coping construction having blocks with 2-way wash surfaces as most familiar in the art, though I will use my device also with a form that I consider preferable, namely, a coping having a 1-way wash, that is, the upper surface of the coping sloping to the roof, to avoid front surface contamination by draining, overhanging icicles, etc.

As an additional packing and sealing factor I provide a plastic cement element 19 which is designed to be installed between the opposing flanges 14 of a strip.

A portion of the packing element 19 is deposited in an inverted strip and the latter then properly adjusted for application in its functioning position. Compression of the strip under the influence of the bolt and nut molds the cement element 19 into shape and position between the inner sides of opposing flanges 14 and against the surface of the blocks, the substance being pressed into the spacing and against the mortar composing the joints and constituting an effective sealing element. Another result upon the compression of the strip as indicated is the pressing of the plastic cement against the sides of the flanges and encoun-

tering an inward movement of the flanges under the compression of the strip and the interior sliding of the lower edges of the flanges towards the axis of the strip whereby the plastic cement is further compressed and forced to fill all interstices. A surplus of the element is exuded through the bolt holes 6 thus further sealing the joint.

I have referred to the packing element 15 installable exterior to the flanges under the strip. This packing element is inserted by suitable tools, that is keyed in, under the laterally extending edges of the sides 13 as spaced from the blocks and preferably after the plastic cement has been compressed within the strip on the blocks. It is obvious that the introduced packing substance 15, which is not necessarily integral, can be made to fill the spaces for which it is provided both because of its own elastic nature and because of the elastic character provided by the material and construction of the strip. The packing element 15 provides an accessory sealer, and means of dressing the edges of the strip.

A considerable degree of adjustability is provided for, since after installation the nuts may be tightened on the bolts to take up looseness in the engagement of strip with block. A strip is easily removable for replacement of packing or of strip.

Attention is called to the structure and service of the upstruck guards 12, as illustrated in Fig. 4, these features serving as seats for the nuts, and also as protective elements to prevent seepage of moisture around the nuts and bolts inwardly to the strips and mortar.

A joint sealed as I have described may be a connection of elements secured together or not, the sealing means being an extra precaution, or a protective or a decorative expedient. My device may be further employed in other types of situations, for example, a long continuous strip may be used as a ridge element applied to a continuous edge or surface as distinguished from an edge or surface constituted of blocks or plates presenting transverse joints; and means for securing a strip suitably to such situation would be provided.

What I claim and desire to secure by Letters Patent is:

1. The combination with coping blocks of a sealer comprising a strip having tapering sides, the sides indent and downwardly inwardly projected forming bearing flanges, packing elements positioned outwardly of said flanges, and bolts engaged with the strips and with the blocks and compressing the strip upon the packing elements.

2. A device of the character described including a metal strip having its longitudinal edges turned inwardly to form an underlap and downwardly to form support-

ing flanges, packing located within the spaces beneath the underlapped portions, and means for securing the strip on a coping.

3. A device of the character described including a metal strip having its longitudinal edges turned inwardly to form an underlap and downwardly to form supporting flanges, packing located within the spaces beneath the underlapped portions and beneath the body of the strip between the flanges, and means for securing the strip on a coping.

4. In combination with aligning coping blocks, a strip having inset supporting flanges at its longitudinal edges engaging the respective blocks, sealing material within the recesses formed by said flanges, and means extending through the strip and between the blocks for securing the strip to the blocks.

5. In combination with spaced coping

blocks, a strip overlying the space between the blocks having downwardly extended sides, backturned to underlap at the longitudinal edges and downturned at the inner edges of the underlaps to form supporting flanges, and bolts connected with the strip having heads underlying the blocks to anchor the strip to the blocks.

6. In combination with spaced coping blocks, a strip overlying the space between the blocks having downwardly extended sides, backturned to underlap at the longitudinal edges and downturned at the inner edges of the underlaps to form supporting flanges, packing beneath the strip between the flanges, packing beneath the strip exterior to the flanges, and bolts connected with the strip having heads underlying the blocks to anchor the strip to the blocks.

In testimony whereof I affix my signature.
THOMAS WIGHT.
